UNITED STATES PATENT OFFICE.

ROLAND CHILTON, OF KEYPORT, NEW JERSEY, ASSIGNOR TO AEROMARINE PLANE & MOTOR COMPANY, A CORPORATION OF NEW YORK.

VALVE MECHANISM.

Application filed August 3, 1922. Serial No. 579,412.

To all whom it may concern:

Be it known that I, ROLAND CHILTON, a subject of the King of England, and a resident of Keyport, in the county of Monmouth and State of New Jersey, have invented certain new and useful Improvements in Valve Mechanism, of which the following is a specification.

This invention relates to improvements in valve operating mechanisms in general, and more specifically to that type of mechanism which is frequently associated with aircraft and other high out-put internal combustion engines wherein over-head inlet and exhaust valves are operated from a common camshaft through the medium of rocking levers.

Conventional practice in such mechanisms involves the use of a spiral spring around the valve stem for returning the valve to its seat and keeping the actuating parts in contact with the cam profile. Springs of this type occupy a considerable length and involve proportionally long valve stems and rocking levers. It is one of the objects of this invention to reduce the weight of all moving parts, which is effected in part by achieving extreme compactness in the whole design, by the use of a flat valve-returning spring disposed above the valve levers, and attached to the valve stems by a new form of unitary link. By this means the valve stems need only be made as long as is required to get adequate guiding surface instead of having to accommodate in addition considerable length of spiral spring. At the same time owing to the angular disposition of the valves, which is necessary in a valve mechanism of this type, relatively short rocking levers result from a shortening of the valve stem.

Small mass in the moving parts is of paramount importance in valve mechanisms in general and this end is additionally achieved in this invention by an organization of parts enabling the practical utilization of rocking levers fabricated from a relatively light material such as the modern aluminum alloys.

Conventional constructions in the rocker arms require these to be made from steel or similar high tensile material which can be hardened because such conventional practice involves a rounded face at the end of the valve levers in contact with the end

of the valve stem, to allow of the oscillation of the valve levers. Such a round contact face has only point or line contact and even when made of hardened material is apt to develop rapid wear. It is accordingly one of the features of the present disclosure that means are provided between the end of the valve stem and its actuating lever, whereby adequate surface of contact is realized between these parts throughout their motion, thus permitting the use of a relatively soft and accordingly light material for the rocker arm.

Accessibility and quickness of disassembly are further objects of this invention to which end this special form of valve link and spring arrangement described below contribute.

A further object of this invention is to provide a valve mechanism wherein all the parts may be pressure lubricated. To admit of this special precautions must be taken to prevent excess oil from the parts so lubricated from reaching the inlet valve guide in excessive quantities. Trouble has been experienced from this source in the past because such oil is drawn down the guide and into the combustion chamber. Accordingly the levers and associated parts are designed to minimize this oil splash.

In the showing of the drawings a detachable type of cylinder head is indicated and while this invention is applicable to non-detachable cylinder heads there are special advantages accruing from the specific construction of the showing, in which the cam-shaft is supported directly in bearings machined in the head casting.

In apparatus of the class described an adjustment for clearance between the operating parts when the valve is on its seat must be provided. This is commonly achieved by a screw in the end of the valve lever contacting with the end of the valve stem and having locking means intended to prevent movement of the screw under vibration. This screw and lock device constitute one of the sources of weight of the moving parts and accordingly this invention contemplates an adjusting means which does not move with the lever. Such means is constituted in the case of the showing by providing the fulcrum pin on which the lever actuates with eccentric end portions so disposed that by a rotation of the fulcrum pin the rocker

arm is displaced upwards or downwards in order to effect the desired adjustment. Means are provided for locking this fulcrum pin when the desired adjustment has 5 been obtained and it is a feature of this invention that this fulcrum pin and its locking means do not add to the weight of the moving parts.

To these and other ends, the invention 10 consists in certain improvements and the combinations and arrangement of parts, all as will be most fully hereinafter described, the features of my invention being pointed out particularly in the claims at the end 15 of the specification.

In the drawings:—

Figure 1 is a fragmentary transverse section of a cylinder head taken on the line 1—1 of Fig. 2, showing the most approved form of my invention.

Figure 2 is a fragmentary side elevation of view in Fig. 1.

Figure 3 is a fragmentary end view of the lever bracket in detail.

Figure 4 is a fragmentary longitudinal section of the lever bracket taken on the line 4 of Fig. 3 showing the eccentric fulcrum pin.

In the drawings 10 designates the cylinder head of an internal combustion engine, 11 the piston, 12 the camshaft, having cams 13, 14; the camshaft 12 is rotated in any suitable manner as by means of the motor through intermediate gears (not shown). The levers 15 are actuated by the camshaft 12, by means of the cams 13, 14 acting on the rollers 16, pivoted in the levers 15, said levers being mounted in the bracket 18 upon the fulcrum pins 19, the 30 rotary motion of the shaft 12 being thus converted into a reciprocating motion which is transmitted in turn to the valve stems 20, which are slideable in the guides 21, thereby opening and closing the valves 22, 23 in pre-determined sequence in the usual manner. The bracket 18 has a housing 18^a with openings 47 through which the levers 15 project, the portion 48 of the housing 18^a acting as a fulcrum for the spring member 29.

As shown in Figures 1 and 2, in the upper end of the valve stems 20, I have formed elongated openings 24; 25 designates the U-shaped links having a lower portion 26 engaging in the opening 24 of the valve stems 20, on the upper end of the links 25 there are formed projecting portions 27 which engage the up-turned ends 28 of a laminated valve spring 29, composed of two 55 substantially flat end portions with an intermediate arcuate portion. The links 25 may be readily disengaged from said spring by the application of pressure to the end of the spring mentioned, the links may 60 then be disconnected from their associated

valve stems by turning the links at right-angles thereto and passing the upper end of the stem out through the openings 30 of the links 25. In the guides 21 there are formed on opposite sides thereof elongated openings 31 which give clearance for the links 25 when in operation; in the event of fracture of the spring 29, the links 25 will engage the guides 21 at the lower portions of the opening 31 and thereby prevent the valves being projected into the cylinder where they would cause serious damage.

As shown in Figure 1 the ends 32 of the levers 15 have recesses 33 formed in the under side to receive a ball 34 having a flat side 35 of approximately the same area as the end of the valve stems 20 and having a constant face to face contact therewith; in the previous art it has been customary to have spherical or cylindrical faces in contact with the flat valve stem ends to allow of oscillating and sliding motion relative to the end of the valve stems, this gives only line or point contact and the resulting high intensity of pressure causes rapid wear; it is one of the features of the present invention that a definite and adequate area of contact is secured between the moving parts.

In Figure 4, I have shown the detail of the fulcrum pins 19 having two mutually concentric end portions 37, 38 and an intermediate relatively eccentric portion 39. The end portion 37 is of greater diameter than the end 38 to give it a greater bearing surface and the pin has been stepped down to permit of the same being readily assembled into the levers, it also has a cut-out portion 40 and a slot 41. The end portions 37, 38 have a bearing in the bracket 18 and the center portion 39 acts as a fulcrum for the levers 15, the cut-out portion 40 is a clearance for the bracket retaining studs 42, furthermore, said cut-out portion 40 prevents the pin from being incorrectly assembled into the bracket 18; in the slot 41 a bar or suitable wrench may be inserted for the purpose of adjustment; upon the tightening of the nuts 43 on the 100 studs 42 the pin 19 will be locked in position by contraction of the bosses 46 of the bracket 18.

Disposed intermediate the two ends of the levers 15 and formed integral therewith are the upwardly and downwardly projecting portions 44, 45, the portions 44 extending exteriorly of the bracket housing portion 18^a; the aforesaid projecting portions acting as barriers to deflect any 110 oil that may be projected in the direction of the valve stems for the reason as heretofore described; 49 is a cover for the above-described mechanism to prevent entrance of dirt and leakage of oil.

Variations may be resorted to within the scope of the invention and portions of the improvements may be used without the others.

5 Having thus described my invention, I claim:-

1. In the art of operating a pair of valves from a camshaft by means of rocking levers, the combination of a flat valve spring, 10 unitary links connecting an end of said spring to each valve and embracing the valve end of the rocking lever, and means between the end of the valve stem and the rocking lever, said means shaped to fit contours on each, the one for sliding, the other for oscillation.
2. In a valve actuating mechanism, the combination of a lever, a valve having a stem, a spring, a one-piece open-ended disengageable link connecting the valve stem and the spring, and a substantially semi-spherical contact member interposed between the end of the valve stem and the lever.
- 20 3. In the art of connecting a flat valve spring to a valve stem, a slot through the valve stem near the end thereof, a proximately U shaped link adapted to be assembled into said slot and having projections capable of engaging the end of the spring.
4. In the art of connecting a valve stem end to a spring, a slot in the valve stem end and a one piece link adapted to be threaded through such slot and provided with abutments for engagement of said spring.
- 45 5. In mechanism of the class described, the combination of a valve having a stem, an actuating lever therefor, an oscillating contact member disposed between the actuating lever and the valve, said contact member having a flat face bearing on the end of the valve stem, a spring, and an open-ended one-piece link forming a connection between the valve and the spring and adapted for disengagement from both of the members set forth.
- 50 6. In the art of connecting a flat valve spring to a valve stem, a slot through the valve stem near the end thereof, a rectangular link having an opening in one side to admit of assembly into the stem with the side of the link opposite the opening engaging the slot, the internal width of said link being greater than the width of said opening so as to provide an abutment for the spring.
- 55 7. In a valve mechanism, the combination of, a valve provided with a slotted stem, a valve lever, a spring, a connection between the valve stem and the spring comprising a disengageable link disposed in the slotted portion of the stem and engaging the spring, and a connection between the valve lever and the stem comprising an anti-friction member having two dissimilar contact faces.
8. In apparatus of the class described, the combination of a pair of valves, valve actuating levers, semi-spherical contact members between the valves and the levers, a camshaft cooperating with one end of the levers, fulcra for said levers, a bracket supporting said fulcra constituting an oil guard over the camshaft end of said levers, a flat valve spring, a one piece disengageable link between said spring and said levers, and means associated with the bracket for supporting the spring.
9. A valve actuating mechanism for valve in head motors, having in combination, a plurality of valves, said valves having stems, 80 a housing, levers fulcrumed in the housing and adapted to actuate said valves, means for eccentrically adjusting the fulcra of said levers, a resilient member supported on the housing and adapted to maintain said valves, normally in their closed positions, one piece link members interposed between said resilient member and the valve stems, and means integral with said actuating levers adapted to interrupt and deflect oil 90 projected in the direction of said valve stems.
10. In a valve actuating mechanism for valve in head motors, the combination of a plurality of valves having stems thereon, 95 levers fulcrumed in a bracket and adapted to actuate said valves, means for eccentrically adjusting the fulcra of said levers, rotatable members having a flat face associated with said valve stems and interposed between the end of the levers and the end of said valve stems so as to act as bearings therebetween, a resilient member, links having an opening, said links connected to the valve stems and engaging the resilient member, means associated with said actuating levers and integral therewith and adapted to interrupt and deflect lubrication material 100 projected in the direction of said valve stems.
11. In the art of operating a stem valve by means of a lever and a spring, an oscillating contact piece supported in the lever and bearing on the valve stem said contact piece oscillating relatively to said lever and 115 not oscillating relatively to said stem, and an open ended link connecting the stem to the spring.
12. In apparatus of the class described, the combination of a housing, a cam shaft 120 therein, levers adjustably fulcrumed in the housing and operated by the cam shaft, a flat valve spring supported on the housing, valves having stems adjacent to said levers and operated thereby, a substantially semi-spherical member between the valve stems and the levers, an open one piece link connecting the valve stem to the spring and projecting portions on the levers acting as 125 oil deflectors.

13. In an internal combustion engine, in combination, a housing, a cam shaft therein, levers mounted on adjustable eccentric fulcrums and operated by the cam shaft, a flat valve spring supported on the housing, valves having stems adjacent to said levers and operated thereby, slots in the valve stems, a substantially semi-spherical member between the valve stems and the levers, 10 an open one piece link in said slots connecting the valve stems to the spring and projecting portions on the levers acting as oil deflectors.
14. In an internal combustion engine, the combination of a housing, a cam shaft therein, levers having cupped ends, said levers mounted on adjustable eccentric fulcrums and operated by the camshaft, a flat valve 15 spring supported on the housing, valves having stems with flat ends adjacent to said levers and operated thereby, slots in the valve stems, oscillating contact members having a flat face, said contact members disposed in the cupped ends of the levers in a manner so as to afford oscillation therein, 20 the flat faces of said contact members bearing on the flat ends of the valve stems so as to afford sliding contact therewith, open ended links disengageably mounted in said slots, abutments on the links to engage the 25 spring, projecting portions on the levers acting as oil deflectors, and a cover portion for the whole.
15. Signed at Keyport in the county of Monmouth and State of New Jersey this 31st 30 day of July A. D. 1922.
- ROLAND CHILTON.
